INVENTOR

Emil F. Horn

ATTORNEY

Lamont Boston
WITNESS:

UNITED STATES PATENT OFFICE.

EMIL F. HORN, OF ASTORIA, NEW YORK.

TURNER OR REVERSER.

Application filed February 19, 1924. Serial No. 693,857.

To all whom it may concern:

Be known that I, EMIL F. HORN, a citizen of the United States, residing at Astoria, Long Island, in the county of Queens and 5 State of New York, have invented new and useful Improvements in a Turner or Reverser, of which the following is a specification.

This invention relates to a turner or reverser for use in connection with the manufacture of fabric belts, which belts constitute part of a dress, suit or overcoat.

The principal object of the invention is the provision of a machine for receiving a fabric belt in what is termed "an inside out" condition and upon operation of the machine, the belt will be ejected in a reverse condition.

Another object of the invention is to provide a machine of this character which includes a belt receiving member capable of being removed for interchangeably receiving tubes of different lengths and diameters for the accommodation of various size belts.

A further object is to provide a turner or reverser which is simple in construction, cheap in manufacture and easy of operation.

With these and other objects in view, the invention resides in certain novel construction and combination and arrangement of parts, the essential features of which are hereinafter fully described, are particularly pointed out in the appended claim, and are illustrated in the accompanying drawing, in which:—

35 Figure 1 is a side elevation of my invention showing the position of the fabric belt about to be reversed.

Figure 2 is a similar view showing the belt in reversed condition and a portion of 40 the belt being ejected from the machine.

Figure 3 is a top plan view of the invention.

Figure 4 is a transverse sectional view on the line 4—4 of Figure 1.

45 In the manufacture of fabric belts, it is the practice to form the belt of a tubular piece of material after which the belt is adapted to be reversed so as to conceal the stitching at the seams, thus assuring a neat and attractive article. It is therefore my

50 purpose to construct a machine for performing this turning or reversing operation

in a more efficient and practical manner and wherein the same is applicable for use in turning belts of different sizes.

Referring more particularly to the drawing, the reference numeral 10 designates a base upon opposite ends of which is mounted brackets 11 and 12. The bracket 12 is larger than the bracket 11 and both brackets are bolted to the base as at 13. The brackets support a pair of horizontal rails 14 which slidably support a movable carriage 15. The carriage 15 includes a head 16 having a horizontally disposed tube 17 supported therefrom. One end of the tube enters an opening 18 in the head and is removably secured thereto by means of a set screw 19. The tube 17 is interchangeable by reason of its detachable connection with the head whereby tubes of various lengths and diameters may be substituted therefor for turning belts of different sizes.

The bracket 12 supports a push rod 20 which is held in the bracket by means of a set screw 21, and which may also be removed if desired. The push rod is stationary and is disposed in alignment with the longitudinal axis of the tube 17 so as to pass centrally therethrough during the reversing operation.

In operation, a tubular fabric belt 22 is passed over the outer end of the tube 17 until the closed end of the belt abuts the end of the tube. The carriage 15 is moved along the rails to cause the push rod to engage the closed end of the belt and carry the belt in a reverse condition through the tube and partially eject the same through the opposite end of the tube where it is pulled out by hand. By this arrangement, the belt is prevented from crowding or sticking in the tube as the metal walls of the tube reduce the friction to a minimum when the belt is passing therethrough.

After the belt has been removed from the machine it is of course understood that the open end of the belt is stitched in the usual manner. When desired to reverse or turn a relatively long belt which is usually closed at both ends and open at its center, each end is turned separately.

While I have described what I deem to be the most desirable embodiment of my invention, it is obvious that many of the details

may be varied without any way departing from the spirit of my invention, and I therefore do not limit myself to the exact details of construction herein set forth nor 5 to anything less than the whole of my invention limited only by the appended claim.

What is claimed as new is:—

A turner or reverser for tubular fabric belts comprising a base, spaced brackets 10 mounted upon said base, rails supported by said brackets, a head slideable over said rails and having an opening therein, a tubular member open at both ends, a set screw for

removably clamping one end of said tubular member against the wall of said opening, 15 a push rod carried by one of said brackets and arranged in axial alignment with the longitudinal axis of said tubular member whereby a tubular belt inserted over said tubular member will be reversed and ejected from said tubular member upon the movement of said tubular member over said push rod.

In testimony whereof I have affixed my signature.

EMIL F. HORN.
